UNITED STATES PATENT OFFICE.

EDWARD D. PRIEST, OF SCHENECTADY, NEW YORK, ASSIGNOR TO PARKER WIRE GOODS COMPANY, A CORPORATION OF MASSACHUSETTS.

GARMENT HANGER.

Application filed January 17, 1923. Serial No. 613,107.

My invention relates to garment hangers and more particularly to such hangers of the collapsible type.

Another object of my invention is to produce such a hanger which will be simple and cheap to manufacture, strong and durable, and so made that its parts may be folded when not in use into a compact form, yet can be readily extended to normal position and locked in such extended position.

The various features of novelty which characterize my invention are pointed out in the claim annexed to and forming a part of this specification. For a better understanding of my invention, reference may be had to the following description taken in connection with the accompanying drawing, in which the single figure is a view of a garment hanger embodying my invention in extended or normal position.

Referring to the drawing, my garment hanger comprises two side arms 1, 2, relatively movable about a vertical axis, a supporting hook 3 and a looped member 4 surrounding a portion of the hook 3.

The garment hanger is also provided with a horizontal member formed of two parts 7 and 8 connecting the outer ends of said side arms and having a joint located substantially in the vertical axis about which said side arms are movable, whereby the hanger may be folded as before described about the vertical axis. The joint may be made in any well known way, but I prefer to use a sleeve 10 fitting over the parts 7 and 8 of the horizontal members. The sleeve surrounds one of the parts, say 8, and is slipped over the other part, say 7, when the hanger is in extended position. The part 8 is shown as being integral with the side arm 1 and connected to the outer end thereof, and the part 7 is shown as integral with the side arm 2 and connected to the outer end thereof. It will therefore be

seen that the hanger, consisting of hook, side arms and horizontal members, may be made of only two pieces of wire.

The looped portion 4 is shown as a single loop with sufficient play about the hook portion 3 to permit the looped portion to be slipped over the hook portion. In this way each of the two pieces of my garment hanger may be separately and completely formed, and then my hanger may be readily assembled by slipping the looped portion 4 over the hook portion 3 into its proper position as shown in the drawing.

It will therefore be seen that my garment hanger is made out of only two integral sections of wire, one of the sections constituting an arm 1 having formed at one end a horizontal member 8 and at the other end an integral supporting hook 3, the other of said sections constituting the second arm 2, having at one of its ends a horizontal member 7 and at the other end an integral looped end 4, the arms 1 and 2 forming a support for a garment and the horizontal members 7 and 8 forming a second garment support.

What I claim as new and desire to secure by Letters Patent of the United States, is:

A garment hanger consisting of only two integral sections of wire, one of said sections constituting an arm having formed at one end a horizontal member and at the other end an integral supporting hook, the other of said sections constituting a second arm having formed at one of its ends a horizontal member, and at the other end an integral looped end to be slipped over said hook to provide a hinge for said sections, and means joining said horizontal members, said arms forming a support for a garment, and said horizontal members forming a second garment support.

In witness whereof, I have hereunto set my hand this 11th day of January, 1923.

EDWARD D. PRIEST.
